UNITED STATES PATENT OFFICE.

JACOB M. WHALBE, OF NEW YORK, N. Y., ASSIGNOR OF ONE-THIRD TO LOUIS LERNER,
OF NEW YORK, N. Y.

BED OF THE FOLDABLE TYPE.

1,247,192.

Specification of Letters Patent. Patented Nov. 20, 1917.

Application filed July 2, 1915. Serial No. 37,632.

To all whom it may concern:

Be it known that I, JACOB M. WHALBE, a citizen of the United States, and a resident of New York, in the county of New York 5 and State of New York, have invented certain new and useful Improvements in Beds of the Foldable Type, of which the following is a specification.

Beds of the foldable type, of which numerous constructions are now extant, were usually employed only for their space saving properties. It is desirable that the same general form of construction should be applicable to more than one use, 10 *i. e.* the substitute for a stationary bed, and the present invention, in exemplifying this idea, provides a combination of structural elements, which can readily be used as a foldable bed, as well as a rocking crib or 15 cradle, with special provisions for guarding the occupant, such as an infant, from falling out of the contrivance under danger of bodily injury.

The first sheet of the drawings discloses in 20 Figure 1, a side elevation of a bed or crib in extended condition, and in Fig. 2, a similar view in folded condition. Fig. 4 is a detail of construction. Fig. 3 is a side view, of a modified form, Fig. 5, a side view of 25 another modification of construction, and Figs. 6, 7 and 8, are cross sectional views of details of construction of the same. Fig. 9 is an end view of a longitudinally foldable bed, Fig. 10, a side elevation thereof.

The reference numerals 1 and 2 indicate 30 the end frames of a bed, supported on rollers or casters 3 and 4. Each post of the frame is provided with a slot, 5 extending from the lower end of the post a considerable 35 distance. The pivots 6, on the post, support the outer ends of the bars 7 and 8, the inner ends thereof being hinged together at 9. One of the bars, adjacent to the hinge, is provided with a pin 10, adapted to be engaged by a slide 11, having a slot 12, and a blade spring 13, is secured to the slide and contacts with the bars, for causing a more secure engagement of the bars. The hinge 40 9 is so disposed on the inner end of the bars, that the latter can swing downwardly only, and when the slide 11, is pushed across the abutting ends of the bars, the bars are rigidly held in position and prevented from being swung in either direction. A series 45 of lazy-tong elements 14, have their ends

pivoted together as at 15, and are hinged together in pairs, as shown at 16, while the end bars have their outer hinges 17, 18, passing the slot 5, enter the posts of the frames and are movable therein. The two uppermost ends of the outer members of the lazy tongs are held on the stationary pivots 6. Brackets 19 and 20, suitably secured to the bed posts, support the outer pivoted ends of the mattress carrying bars 21, 22, the inner 50 ends of which are hinged, as at 23.

Screw bolts 24 are provided, near the lower ends of the bed posts, having wing nuts 25, for holding a sliding slotted block 26, carrying the rockers 27. This bed may 55 be used as an ordinary bed, when the rockers are lifted off the floor, and as a rocking cradle, when they are lowered to extend beyond the casters 3.

The modification in Fig. 3, shows the ends 60 of the bars 7, 8, bent, as at 28 and 29, and located within the hollow of the bed post. The pivot 6, of course, holds these ends in the usual manner.

The arrangement shown in Figs. 5, 6, 7 65 and 8 is characterized by the supports 30, secured to the bed posts 1 and 2 and having slots 31. A pin 32, at the outer end of each channel bar 33 and 34, and surrounded by a helical spring 32', is vertically movable in 70 the slots, so that the bars 33, 34 which are hinged together at their inner ends, as at 35, can be lifted to a sufficient extent, to free the upper joint of the lazy-tongs 14, normally located within the channel of the bars. 75 Blade springs 36, provide a secure engagement between the walls of the channel and the pivot joint. In this modification, the bars fold downwardly, but only after they have been disengaged from the lazy-tongs by 80 lateral movement of the latter on the hinge pins 32, against the springs 32', whereupon the lazy-tongs can be folded together as already described.

Figs. 9 and 10, illustrate the invention as 85 applied to a longitudinally foldable bed, the upper bars are shown at 37, 38, the locking slide at 39.

I claim—

In a bed frame, the combination with 90 tubular end supports having longitudinal slots in their proximate sides, sectional side bars extending inward through the slots, pivoted in said supports, of hinges connecting the sections of said bars, slides movable 95

on one section of said bars preventing said hinges from operating when placed there-over and a plurality of lazy tong elements the end members thereof being pivoted with said side bars in said supports, said elements being operable in the mentioned slots.

Signed at New York in the county of

New York and State of New York this 19th day of June A. D. 1915.

J. M. WHALBE.
